UNITED STATES PATENT OFFICE.

FREDERICK N. ROSS, OF DETROIT, MICHIGAN, ASSIGNOR TO THE BUTTON ATTACHING MACHINE COMPANY OF WATERBURY, CONNECTICUT, OF WATERBURY, CONNECTICUT, A CORPORATION OF CONNECTICUT.

BUTTON-ATTACHING MACHINE.

Application filed February 14, 1925. Serial No. 9,088.

To all whom it may concern:

Be it known that I, FREDERICK N. Ross, a citizen of the United States, residing at Detroit, in the county of Wayne and State 5 of Michigan, have invented certain new and useful Improvements in Button-Attaching Machines, of which the following is a specification.

This invention relates to a button attaching machine and more particularly pertains to the means for guiding and positioning the button on the button supporting member.

In similar machines of the prior art it has been customary to use a pair of fingers each 15 pivoted to one side of the machine and yieldingly forced towards each other and so positioned as to form a guide for a button or similar article, which is adapted to be fed to a supporting member which moves. 20 These fingers are arranged to spread upon the raising of the supporting member to allow the same to pass between said fingers. One difficulty with this type of positioning fingers is that the same are assembled in the 25 machine with some difficulty and also it is impractical to provide manual means for spreading these fingers when something goes wrong so that the operator can get behind the fingers. The object of my invention 30 is to overcome these difficulties and to provide a single finger which may be more easily assembled in the machine and which can be manually controlled by the operator to quickly retract the same so that the 35 operator may get behind the fingers when anything goes wrong.

A further object is to provide a better guide for the button which is always in adjustment and does not require a periodical 40 adjustment as is sometimes necessary when using a pair of spreadable fingers. In addition, my construction is simpler, more economical and also conforms to the outline of the machine structure so as to 45 present a smooth and unbroken surface towards the operator.

A still further object is the arrangement 50 of the single retractable finger, whereby the same may be more readily cleaned by removing any accumulation of dirt or grease which might adhere to the under side of the finger and prevent the smooth and efficient movement of the finger when the same is retracted to allow the button or

similar article to be projected into the attaching mechanism by the movement of the button supporting means.

In the drawings:

Fig. 1 is a front elevation of a button attaching machine showing my improved form of guiding finger secured thereon.

Fig. 2 is a partial vertical detailed section taken approximately on the line 2—2 of Fig. 1.

Fig. 3 is a view similar to Fig. 2, but showing the finger retracted.

Fig. 4 is a vertical sectional view taken approximately on the line 4—4 of Fig. 2.

Fig. 5 is a detail in perspective of the finger.

Fig. 6 is a horizontal section, taken on the line 6—6 of Fig. 1.

Fig. 7 is a plan view of the device, showing the finger unretracted and taken approximately on the line 7—7 of Fig. 1.

Fig. 8 is an elevational view of a ring button.

The details of the machine need not be described in detail as this structure is immaterial so far as this invention is concerned. It will be sufficient to state that the power is imparted to the shaft *a*, which through suitable mechanism, as described and claimed in my prior Patent No. 1,508,253, will operate suitable attaching mechanism *b*, which will attach a split ring through the eye of a ring button to lock it onto a piece of fabric. The button-supporting means *c* is slidably supported in the groove *d* of the machine structure. The lower end of this button supporting means is provided with a pin *e* which is adapted to be engaged by the forked arm *f* which is rocked by the operating mechanism.

This plunger *c* is provided with a button seat *g* and a button chute *h* feeds a plurality of buttons downwardly, and when the button supporting means or plunger is lowered below the mouth of the chute, a button is allowed to fall by gravity onto the button seat, whereupon the plunger immediately rises.

For the purpose of guiding the button onto the seat and positioning the same thereon, it is necessary to provide additional means for guiding the button from the time it leaves the chute until it comes to rest. This is accomplished by the finger *i*,

which I pivot to the machine by providing the finger with a pair of inwardly extending ears *j*, which are adapted to pass through the slots *k* in the front of the machine and 5 pivoted to the machine by means of the pins *m* as clearly shown in Fig. 6. A spring *n* attached to this finger and anchored to the machine frame as at *o* normally tends to pull the finger towards the machine and 10 hold the same in the position as shown in Figs. 2 and 7.

This finger is provided at its lower end with a lip or ear *p* which the operator may 15 press down with the thumb when he desires to manually move the finger. The other end of the finger is turned inwardly as at *q* and is arranged to project over and above the button seat and abut against the mouth of the button chute. This extension *q* is provided with the slot *r* which is in registration 20 with the mouth of the button chute and serves as a guide for the button by guiding the loop of the eyeleted button as shown in Fig. 8. This correctly positions the eye or 25 loop of the button so that the same may be properly injected into the attaching mechanism. After the button has been seated upon this button seat *g*, the machine mechanism raises the button supporting member 30 and the fingers *s* pivoted to the side of the machine are yieldingly held against the button by means of the springs *t* for the purpose of holding the button on the seat until 35 the button *i* starts to enter the attaching mechanism.

Upon the raising of the button plunger, the front edge of the plunger engages the 40 inclined under side of the inwardly extending projection *q* and forces the same outwardly into a position as shown in Fig. 3. This is what I call the retracted position, and when the button plunger is lowered again, the finger immediately springs in 45 and registers the slot *r* with the mouth of the chute, so that the next button is correctly guided and positioned on the button seat.

In the specification and claims I have described this finger as serving to guide and 50 position a button in the machine, but obviously with slight modifications of structure that any mechanism may do without exercising inventive ability, the finger may be utilized in connection with other elements 55 such as a tack or other shaped buttons. In the claims, I have used the term button, and I desire the claims to be interpreted to mean any one of these button elements, whether the device is adapted for guiding in position 60 the tack, or any form of button head.

What I claim is:

1. In a button attaching machine, the combination of a support, a movable button supporting means supported thereby and including a button seat, feeding mechanism

for feeding a button to the button supporting means, and a single retractable finger carried by said support and provided with means for guiding the button from the feeding mechanism onto the button seat and properly positioning the button thereon, said finger retracted upon movement of said button supporting means. 70

2. In a button attaching machine, the combination of a stationary support, a button supporting means slidably supported thereby and provided with a button seat, feeding mechanism for feeding a button to the button supporting means, and a single retractable finger hinged to said support and provided with means for guiding the button from the button feeding mechanism onto the button seat and positioning the same thereon, said finger retracted upon movement of said button supporting means. 75

3. In a button attaching machine, the combination of a support, button supporting means including a button seat slidably supported by said support, button attaching mechanism, a feeding mechanism for feeding a button to the button supporting means, a single retractable inverted L-shaped finger, the foot of said L-shaped finger being inclined to the horizontal and having its under side arranged to be engaged by the slidable button supporting means, whereupon the finger is thrust aside to allow the button to be projected into the attaching means, and means on the said foot of the L-shaped finger for guiding the button from the button feeding mechanism onto the button seat and positioning the same thereon. 90

4. In a button attaching machine, the combination of a support, button supporting means slidably supported thereby and including a button seat, feeding mechanism for feeding a button to the button supporting means, a single retractable finger provided with means for guiding the button from the feeding mechanism onto the button seat and positioning the same thereon, and a forwardly extending lip on said finger, whereby the operator may manually move the finger by pressure applied on said lip. 105

5. In a button attaching machine, the combination of a support, attaching mechanism, button supporting means including a button plunger provided with a button seat movable with respect to the support, button feeding mechanism, means for moving the button plunger to position a button in cooperative relation with the attaching mechanism, and a single finger hinged to said support and provided with means for guiding the button from the feeding mechanism to the button seat, but retractable upon the moving of the button plunger. 110

In testimony whereof I have affixed my signature.

FREDERICK N. ROSS.
